UNITED STATES PATENT OFFICE

CHARLES L. MCCUEN, OF LANSING, MICHIGAN, ASSIGNOR TO GENERAL MOTORS CORPORATION, OF DETROIT, MICHIGAN, A CORPORATION OF DELAWARE

OIL PAN

Application filed June 8, 1928. Serial No. 283,900.

This invention relates to improvements in crankcase oil pans for internal combustion engines and involves the provision of a series of sediment wells or traps in the bottom of the oil pan.

Due to the fact that the lubricating oil becomes contaminated and dirty in use the common practice in the past has been to change or replace the oil supply after a certain short period of use. By the employment of sediment wells or traps in accordance with the present invention, the dirt particles suspended in the oil that tend to settle out at times when the engine stands idle will be entrapped and held against recirculation through the engine lubricating system. Since the amount of dirt picked up by the oil between idle intervals is small the oil will remain comparatively clean and free from impurities for a greater length of time.

It is among the objects of the present invention to provide an oil pan that will be simple and economical in manufacture, easy to assemble and install either on existing engines or as standard equipment on new engines, efficient and care-free in use, and which will be unlikely to get out of order or require the replacement of parts.

It is a further object of the invention to provide a unitary assembly of spaced plates that may be detachably secured on the bottom of the oil pan to afford a plurality of small sediment traps which may be readily removed at such times as may be necessary to facilitate the cleaning or disposition of accumulated sediment.

Another object is to provide a pad or matting of flexible fibrous material for interposition between the plate assembly and bottom wall of the pan to afford a seal for the bottom edges of the plates against the escape of dirt particles and to which the dirt particles will readily adhere.

A further object of the invention is to provide a crankcase pan having a bottom wall that has inclined portions leading to a sump for the pump forming a part of a pressure feed lubricating system, the plate assembly before mentioned being secured to such in-

clined portions and forming the sediment wells, whereby a greater supply of oil than would be ordinarily employed will not be required because of the provision of the sediment wells. Except for a comparatively small amount of oil that would be contained in the sediment wells, all the oil in the pan would be available for circulation to the lubricating system.

Other objects and advantages will be apparent from the following specification taken in connection with the accompanying drawing, wherein,

Figure 1 is a fragmentary side elevation of an engine cylinder block and crankcase with the oil pan associated therewith shown in section after having been taken on line 1-1 of Figure 2.

Figure 2 is a transverse sectional view of the oil pan on line 2-2 of Figure 1.

Figure 3 is an enlarged detail sectional view of one end of the plate assembly secured in the oil pan.

Figure 4 is a detail perspective view of a portion of the plate assembly showing one method of connecting the parts together.

Referring to the drawing, the numeral 1 indicates an engine cylinder block having a crankcase 2, and the character 3 marks the crankcase pan or oil reservoir that is removably secured on the bottom of the crankcase 2. The bottom of the crankcase pan consists of portions 4 and 5 that converge or are inclined downwardly from the sides to a substantially horizontal central portion 6 in which is located the drain plug 7. Secured to each of the inclined portions 4-5 is a tray or assembly of baffle walls comprising a pair of spaced side members 8 and a succession of plates 9 of substantially ogee or Z-shape which extend between, and are connected as by welding, with the side members 8 and in spaced relation with each other. The spaces between the succession of Z-shaped plates form settling chambers or wells for the dirt that settles out of the oil when the engine is standing idle. In dropping, the dirt particles are directed by the slanting webs of the Z-shaped plates through the restricted openings between the succeed-

ing plates and into the intermediate dead spaces or wells where they are trapped and held against recirculation when the engine is again started because of the lack of turbulence of the liquid in the wells. A felt pad or matting 10 is preferably placed between the lower edges of the plates and the bottom of the pan, and the studs or bolts 11 serve to detachably hold the assembly of plates in place. When it is desired to remove the accumulation of sediment in the traps, the pan is taken off, and upon detachment of the bolts 11, the plate assembly, as well as the matting 10, can be lifted out and flushed 15 clean.

At the junctures of the inclined portions 4 and 5 with the central portion 6 there are secured, as by welding or soldering, a pair of spaced partitions or baffle walls 12 which define a sump for the pump 13 having a screened intake device 14 and which extends through a flanged opening 15 in the cover plate 16. The side portions of the cover plate, which are secured as by screws or bolts 20 17 to the partition walls 12, are inclined downwardly and overhang the plate assembly so that any sediment deposited on the cover plate will tend to work down and so off into one of the settling wells or traps. A 25 plurality of openings or apertures 18 are provided in each wall 12 at substantially the height of the endmost plates of the trap unit to permit entrance of liquid into the sump and also provide an additional sediment well 30 between the wall and the adjacent plate. 35

The present device is intended to take the place of customary oil filters now in use and it will find particular application on engines used for propelling motor vehicles or those 40 that are not in constant operation. During the idle intervals between operating periods the dirt particles will tend to separate from the oil and drop into and be trapped by the sediment wells. Since the amount of impurities picked up by the oil during a single 45 operating period is normally quite small it will be obvious that the dirt particles will be precipitated and entrapped as quickly as they enter the oil supply. For this reason 50 the life of the lubricating oil is materially prolonged and the necessity for frequent replacement is eliminated. With the average motor vehicles engine the accumulation of sediment will not call for removal until after 55 from two to three years of usage.

I claim:

1. A liquid reservoir, a succession of spaced baffle walls in said reservoir forming a plurality of sediment traps, and a 60 cushioning strip in the bottom of each trap.

2. In an internal combustion engine subject to inherent vibrations upon operation, an oil pan having a bottom wall, a succession of spaced baffles cooperating with the 65 wall to provide a plurality of sediment

traps, and cushioning material interposed between the baffles and said bottom wall and extending across the bottom of the traps.

3. A liquid reservoir, a tray removably secured on the bottom thereof and comprising a pair of spaced side members, and a plurality of plates substantially Z shaped in vertical cross section mounted on and extending between said side members in corresponding spaced succession to provide sediment wells. 70

4. An oil pan for internal combustion engines, including a bottom wall having a substantially horizontal central portion and downwardly inclined side portions, sediment traps associated with said inclined portions and consisting of a plurality of plates of Z shape in vertical cross section arranged in spaced succession, a pair of spaced baffle walls secured to said central portion having openings therein at substantially the height of the lowermost trap, a cover plate secured to said walls over the intervening space and projecting therebeyond over the endmost sediment traps, and forming with said walls a pump sump. 80

5. In an internal combustion engine or the like, an oil pan having a bottom wall, means cooperating therewith to form a plurality of traps for settling, including a group of substantially Z-shaped plates arranged in regular spaced succession, with the corresponding upper and lower end portions of the several Z plates in spaced parallel planes, the adjacent end portions of the lower set forming one with another, the side walls of the several traps and the end portions of the upper set cooperating with the intermediate portions of the Z-shaped plates to guide the settling into the traps, said intermediate portions lying in substantially the same plane, providing covers for the traps and being of a length slightly less than the space between succeeding plates so that each intermediate portion ends short of the next adjacent plate to afford a restricted opening into the trap. 95

6. The structure of claim 5 wherein the intermediate portion of each plate is inclined upwardly from the lower end portion to the upper end portion. 100

7. The structure of claim 5 and a cushion element in the bottom of each trap. 115

8. In an internal combustion engine, an oil pan having a bottom wall, means cooperating therewith to form a plurality of traps for settling, including a group of plates arranged in spaced succession and having corresponding angular portions, with one set of the corresponding portions extending upwardly from the bottom wall of the pan and forming one portion with the next adjacent portion, the side walls of the traps, and other set of angular por- 120

tions forming covers for the traps, each cover portion extending toward but ending short of the next succeeding plate to provide a restricted entrance opening to the trap therebeneath.

5 9. In an internal combustion engine, an oil pan having a bottom wall, means cooperating therewith to form a plurality of traps for settling, including a group of

10 plates arranged in spaced succession to form the side walls of the several traps, and an angular cover portion on the upper end of each plate projecting toward and ending in spaced relation with the next succeeding

15 plate.

10. The structure of claim 9 wherein each angular portion terminates in an upturned flange that cooperates with an adjacent angular portion to provide a flaring mouth to

20 the trap entrance.

11. The structure of claim 9 wherein a felt pad covers the bottom of each trap.

12. In an internal combustion engine, an oil pan having a bottom wall, means cooperating therewith to form a plurality of traps for settling, including a group of

25 plates arranged in spaced succession to form the side walls of the several traps, and an angular portion on the upper end of

30 each plate, projecting in an inclined plane toward the next succeeding plate and ending in spaced relation therewith to afford a cover for and a restricted entrance to the trap therebeneath and an inclined guide to

35 the entrance of the next adjacent trap.

In testimony whereof I affix my signature.

CHARLES L. McCUEN.
